UNITED STATES PATENT OFFICE.

ANSON J. BENTLEY, OF NILES, OHIO.

FREEZING CAN.

Application filed January 6, 1922. Serial No. 527,297.

To all whom it may concern:

Be it known that I, ANSON J. BENTLEY, a citizen of the United States, and a resident of the city of Niles, county of Trumbull, and State of Ohio, have invented an Improvement in Freezing Cans, of which the following is a specification.

The present invention relates generally to improvements in freezing cans used in the manufacture of ice of the type wherein means are provided for forcing air into the can at or near the bottom so that it may circulate through and agitate the water which is to be frozen according to the usual practice in what is known as the raw water system of ice-making. The invention is particularly directed to an improved construction of means to connect the air supply with the can.

The invention about to be described is of particular utility in connection with a form of freezing can shown in my co-pending application, Serial No. 433,163, in which the means for conducting air to a point at or near the bottom thereof consists of an integral tube or conduit formed by overlapping the adjacent wall members and spacing one from the other along the overlapped portions. In cans of this type, as compared with cans having inserted tubes, some form of connector must be provided near the top of the can inasmuch as the walls of the conduit must necessarily be flush with the top of the can, not only to avoid any damage that would be occasioned in handling a can having an extension, but also to reduce the cost of manufacture. It is impractical merely to insert a nozzle in such a conduit because galvanized metals

such as are used in cans of this character are not sufficiently smooth to permit the formation of an air-tight connection with other surfaces. Further, the cans must be more or less roughly made in order to afford an inexpensive structure and it would be highly impractical to attempt making the upper ends of the conduits of such identical cross-sections in the various cans as would be required to permit a readily removable air-tight connection between the nozzle member, which would have to be used with many different cans, and the conduit. Identical similarity between the upper ends of the conduits would be necessary. It will readily be seen that such a

construction is not only highly impractical, but is of such a character as to require such exactness in the manufacture of the entire can that the cost would be prohibitive. Furthermore, whenever any of the conduits are impaired near their upper ends, it is impossible to attempt making an air-tight joint with the nozzle member and the entire can is accordingly useless so far as its application to the raw water system of ice-making is concerned.

It is an object of this invention to provide an inexpensive connecting member of a metal similar to bronze which may be readily fixed permanently to the conduit above described and into which a nozzle may be readily inserted and attached forming an air-tight connection therewith to eliminate thereby the necessity of forming a temporary joint between the galvanized walls of the conduit and nozzle directly; to so construct the cans and integral conduits that the connecting member may be permanently attached without danger of its being knocked loose or impaired in any way by the rough use to which the cans must necessarily be subjected. Other objects will be apparent from the description.

A preferred embodiment of the invention has been selected for purposes of illustration and description and is shown in the accompanying drawings wherein,

Figure 1 is a perspective view of a freezing can embodying a preferred form of the invention;

Figure 2 is an enlarged detail view of a corner of the can shown in Fig. 1, having the solder omitted for simplicity of illustration;

Figure 3 is an enlarged detail view of a corner of the can in Fig. 1, before the connecting member is attached;

Figures 4 and 5 are detail views of the connecting member;

Figure 6 is a detail view of the nozzle; 100

Figure 7 is a top plan view of one of the corners of a can showing another way of assembling the connecting member; and

Figure 8 is a detailed view showing the connecting member soldered to the can. 105

The general construction of the freezing can shown herein may be that of my co-pending application, Serial No. 433,163, filed December 27, 1920, in so far as the form of the side walls, the bottom and the con- 110

duits, except as hereinafter specified, and the joining of the several parts are concerned.

- The can shown comprises two pieces of 5 galvanized sheet metal, one of which forms the side wall 1 and the end wall 2, while the other forms the side wall 3 and the end wall 4. The third piece of sheet metal is suitably cut to form the bottom 5 of the can. 10 The side walls may be formed, if desired, with grooves 6 for stiffening purposes. The air conduit 10 is preferably located at one of the seams of the can where the two sheets of metal overlap, and is made by deforming 15 one or more of the overlapping sheets. Referring to Fig. 1, it will be seen that the seams come at diagonally opposite corners of the can and that there is a substantial overlapping of the metal of side 2 on side 20 3. A groove 7 is formed near the edge of the sheet forming side 3, this groove extending along the edge from a point near the top to a point near the bottom of the can. When the two sheets of metal which have 25 been suitably cut and bent to form the side and end walls of the can are brought together for riveting in the usual manner, the overlapping edge of the sheet 2 will, in cooperation with the grooved edge of sheet 3, 30 form a conduit which may be utilized for the introduction of air to the bottom of the can. The groove 7 may extend substantially the entire length of the side 3 and an opening is formed at the lower end preferably 35 by cutting away part of the metal of the groove to permit the escape of the air. If desired, a hole may be made at the lower end of the conduit and other holes may be made along the conduit. When the sides have been 40 brought together and riveted, the bottom piece may be assembled with the rest of the can and suitably riveted in place. A reinforcing band 9 may be placed around the top of the can and likewise riveted in place. 45 It is customary to render the seams of the can fluid-tight by means of soldering, and the soldering of the corner seams in the usual manner will make the conduit fluid-tight as well. It will be observed that the construction just described provided a very durable means of introducing air into the can. The walls of the air conduit are of the same strength as the walls of the can itself and when rivets are placed at each side of the 55 conduit there is little or no danger of the conduits becoming jammed so as to interfere with the passage of air therethrough. However, it will be noted that in constructing a conduit in this manner, it is impracticable to form an air-passage in the galvanized wall members having identical cross-sections in the various cans. In fact, if sufficient care were taken to construct cans having grooves of identical cross-sections near 60 the top, unless these grooves which are sub-

stantially reinforced are of a thicker metal than is ordinarily used in the construction of freezing cans they would soon be flattened or otherwise deformed by the removal of the cakes of ice. Any irregularity or deformation at the upper end of the conduit would completely prevent the formation of an air-tight joint between the conduit and nozzle. Furthermore, this defect could not be remedied without replacing the entire can since 70 the conduit is integral with the walls of the can. For this reason it has been found that nozzles or tubes cannot be effectively applied directly to the conduits to connect temporarily the source of compressed air to the 75 cans since such a joint will never be air-tight.

In the present invention, the grooved wall of the conduit 10 hereinbefore described is slotted at its upper end, as shown at 11. This 85 slot exposes a substantial part of the wall member 2 and permits a connecting member 12 hereinbefore described to be soldered thereto after it has been inserted in the conduit 10. This slot not only permits the connecting 90 member 12 to be rigidly and permanently attached to the end of the conduit 10 by permitting the solder to be applied to a very substantial portion of its surface, but it also permits the attachment of the connecting 95 member in such a way that it is a continuation of the conduit 10 and occupies substantially the same space as the cut-away portion which has been removed from the grooved wall. It will be noted that the connecting 100 member 12 furnishes no protrusions which will come in contact with the cake of ice as it is removed from the can and accordingly there is no danger of its being impaired.

The connecting member 12 hereinbefore 105 referred to is preferably made of bronze or some similar material which, because of its smoothness, is adapted to form air-tight joints with other metals. There is provided a tapered end 13 which is adapted to be inserted into the conduit 10 and a flat side 14 which contacts with the wall member 2 and is secured in position by solder 25 which is permitted to run between the edges of the slot and the connecting member 12 and also 110 between the flat portion 14 and the wall member 2, thus firmly holding the connecting member in place and also forming a permanent continuation of the conduit 10. There is also provided an air passage 20 in 115 the connecting member which may have its cross-section reduced at the tapered end of the member 12. The upper part 22 of the air passage 20 is of such a size that it will readily permit the insertion of the tapered 120 portion 16 of the nozzle member 15. Since both of these members are made of metal similar to bronze, a perfect air-tight connection is made between the nozzle member 15 and the connecting member 12 by the inser- 130

tion of the end 16 into the upper part of the air passage 20. Integral with the tapered end 16 of the nozzle is an enlarged portion 17 which is formed into a nipple 18 at its end 5 to facilitate the attachment of a hose thereto. An air passage 23 is provided which communicates with the air passage 22 of the connecting member.

It will be noted that while it would be 10 highly impractical, if not impossible, to so construct the upper end of the conduit 10 to form a snug or air-tight joint with the nozzle member 15, an inexpensive connecting member 12 has been provided and interposed between the conduit 10 and the nozzle member 15 and which can be permanently attached to a conduit of any cross-section and which will always form with the nozzle an air-tight joint. In case of impairment of this member, it may be readily replaced by melting the solder which holds it in position. The cost of this additional member is slight, yet it enables a perfect 20 air-tight connection to be made with the conduit 10 regardless of its cross-section and regardless of the thickness or quality of galvanized metal that is used in its construction.

Another form of applying the invention 30 is shown in Fig. 7 wherein the reinforcing band 9 and the sheet metal 2 are shaped to provide a groove 20 opposite the groove 7 and adapted to permit the insertion of the connecting member 12 into the conduit 35 10 without necessitating its protrusion beyond the outer contour of the groove 7. It will be seen that the groove 7 forms a pocket into which the connecting member fits and in which it is secured by means of solder 40 as hereinbefore described. It will also be noted that in this case it is not necessary to flatten one side of the connecting member 12 since the groove 24 and groove 7 form a substantially round conduit at the top 45 and a round connecting member can accordingly be used without protruding beyond the space occupied by the cutaway portion.

As various embodiments may be made in the invention above set forth, it is to be 50 understood that all matter herein set forth is to be interpreted as illustrative and not in a limiting sense.

I claim:

1. A freezing can for use in the manufacture of ice having two wall sections riveted together to form a longitudinal seam, a conduit provided by deforming one of said wall sections, a connecting member adapted to be inserted in said conduit and 60 to be attached to one of the walls of said conduit, and the other of said walls having a slot to facilitate the securing of said connecting member in said conduit.

2. A freezing can for use in the manufacture of ice having two wall sections 65

riveted together to form a longitudinal seam, a conduit provided by deforming one of said wall sections, a tubular connecting member adapted to be inserted in the upper end of said conduit, and said deformed wall 70 section having a portion cut away at the upper end of said conduit whereby said inserted connecting member may be attached to said other wall section to form a continuation of said conduit substantially within the space occupied by said cut-away portion.

3. A freezing can for use in the manufacture of ice having two wall sections riveted together to form a longitudinal seam, a conduit provided by deforming one of said wall sections, a tubular connecting member adapted to be inserted in the upper end of said conduit, said deformed wall section having a portion cut away at the upper end of 80 said conduit whereby said inserted connecting member may be attached to said other wall section, and the contacting surface of said other wall section and said connecting member having a formation with respect to each other to permit said connecting member to lie within the space occupied by said cut-away portion.

4. A freezing can for use in the manufacture of ice having two wall sections 95 riveted together to form a longitudinal seam, a conduit provided by deforming one of said wall sections, a tubular connecting member provided with an air passage therethrough adapted to be inserted in 100 the upper end of said conduit, said deformed wall section being cut away at its upper end whereby said inserted connecting member may be attached to said other wall section to form a continuation of said conduit substantially within the space occupied by said cut-away portion, and a nozzle member 105 adapted to be inserted into said air passage forming an air-tight joint with said connecting member.

5. A freezing can for use in the manufacture of ice having the metal of one wall formed to provide an air conduit extending down the wall of the can and a connecting member secured in the upper end of the conduit, the wall of the conduit being cut away 115 to facilitate securing the connecting member in position.

6. A freezing can for use in the manufacture of ice having the metal of one wall 120 formed to provide an air conduit extending down the wall of the can and a connecting member secured in the upper end of the conduit and substantially even with the top 125 of the can, the wall of the conduit being cut away to facilitate securing the connecting member in position.

7. A freezing can for use in the manufacture of ice having wall members coacting to provide a complete air conduit, and a 130

tubular connecting member arranged in the upper end of said conduit having a bore adapted to receive a hose connector.

8. A freezing can for use in the manufacture of ice having wall members coacting to provide a complete air conduit, and a tubular connecting member arranged in said conduit with its upper end substantially even with the top of the can and adapted to receive a hose connector.

9. A freezing can for use in the manufacture of ice having wall members coacting to provide a complete air conduit, and a tubular connecting member permanently secured to the can and connected to said air conduit and having a bore adapted to receive a hose connector.

10. A freezing can for use in the manufacture of ice having a downwardly extend-

ing conduit formed between parts of the 20 can secured together by two rows of rivets and spaced apart therebetween and having secured in the upper end of the conduit a tubular connector arranged for attachment of an air nozzle.

25

11. A freezing can for use in the manufacture of ice, having an air conduit extending downwardly from the top thereof and formed by and between integral overlapped edge portions of wall material, 30 means for fastening said wall material on both sides of said conduit and a bushing formed to receive an air hose connector arranged in the upper end of the air conduit.

In testimony whereof, I have signed my 35 name to this specification this 3rd day of January, 1922.

ANSON J. BENTLEY.
